(Cl. D92—2)

To all whom it may concern:

Be it known that I, John J. Maibach, a citizen of the United States, residing in New York, county and State of New York, have invented a new, original, and ornamental Design for Bedspreads or the like, of which the following is a specification, reference being had to the accompanying drawing forming a part thereof.

The figure is a top plan view of a bedspread illustrating the new design.

I claim:

The ornamental design for a bedspread or the like, substantially as shown.

JOHN J. MAIBACH.
